UNITED STATES PATENT OFFICE.

PATRICK MEEHAN, OF LOWELLVILLE, OHIO.

BLAST-FURNACE TOP.

SPECIFICATION forming part of Letters Patent No. 700,963, dated May 27, 1902.

Application filed April 12, 1901. Serial No. 55,505. (No model.)

To all whom it may concern:

Be it known that I, PATRICK MEEHAN, a resident of Lowellville, in the county of Mahoning and State of Ohio, have invented a new 5 and useful Improvement in Blast-Furnace Tops; and I do hereby declare the following to be a full, clear, and exact description thereof.

My invention relates to the construction of 10 blast-furnace tops, and has for its object to improve the construction of furnace-tops whereby a free expansion and contraction of the masonry shaft is permitted without disturbing the furnace-top, whereby the life of 15 the top of the stack is greatly increased, whereby the amount of fine ore carried out by the gases is reduced, and whereby damage due to explosions is greatly decreased, and in general to increase the strength and 20 durability of furnace-tops.

Heretofore in blast-furnaces it has been the practice to place the gas-outlet ports to which the downcomer is connected, in the upper portion of the side wall of the furnace, 25 and the top was flat and rested upon the top of the masonry shaft. This construction not only weakened the top of the masonry shaft, but as the gases were taken out through said side walls they would carry with them a considerable amount of the fine ores, and the expansion of the masonry shaft was liable to lift 30 off the top of the furnace resting thereupon. Furthermore, any slight excess of pressure in the furnace-chamber would also lift the top off 35 the shaft, thereby necessitating frequent repairs, and whenever an explosion occurred the damage to the furnace-top was very great, for the reason that the hopper projecting through the top of the furnace did not extend down 40 into the stack sufficiently far to prevent the stack being filled up with stock very close to the top of the stack, so that when an explosion occurred there was no space into which the exploding gases could expand, and as a 45 consequence the top was liable to be blown off or the furnace otherwise damaged.

It is the object of my invention to overcome all of these defects; and to these ends it comprises, generally stated, a furnace provided with a globe-shaped top and with a hopper projecting through the same and down

into the stack to such a distance that the stock cannot be filled in close up to the top, thereby leaving at all times a considerable space in said globe-shaped top and above the 55 stock-line, into which space the gases can expand upon explosion, the gas-ports connected to the downcomers extending through said globe-shaped top, so that the masonry wall of the shaft is not weakened thereby, and 60 said ports thus being a considerable distance above the lower end of the hopper, whereby the amount of fine ores carried out by the gas is greatly reduced.

My invention also comprises certain improvements in the manner of supporting this globe-shaped top on the shell of the stack, so as to permit free expansion of the masonry walls of the stack, and also certain details in construction of the top of the wall of the shaft 70 which will permit this free expansion and greatly increase the life of said stack.

In the accompanying drawings, Figure 1 is a vertical section through the top of the furnace. Fig. 2 is a side elevation of a portion 75 of the hopper. Fig. 3 is a horizontal section of the same on the line 3 3, Fig. 2. Fig. 4 is a horizontal section through several of the hollow blocks on top of the masonry shaft, and Fig. 5 is a vertical sectional detail of a modification of the upper part of the stack.

The shaft of the furnace is constructed as usual and comprises the masonry shaft 1, the metallic shell 2 around the same, and the comparatively soft or porous compressible 85 material 3, such as furnace-cinder, placed between the masonry shaft 1 and the outer shell 2 in order to permit radial expansion and contraction of the masonry shaft. The top of the shaft 1 is formed of one or more tiers 90 of hollow blocks, (the drawings showing two such tiers or blocks;) but more or less than two may be used, if desired. These blocks are preferably formed of cast metal and will not wear away easily by the ore falling on 95 them from the hopper nor by the fine ores which are carried up by the gas, which fine ores act somewhat as a sand-blast and quickly wear away the ordinary brick or masonry top. The blocks 4 of the lowermost tier are substantially rectangular in shape except that they are formed on an arc to correspond to 100

the circular shape of the stack. The blocks 5 of the upper tier are substantially triangular in vertical cross-section, thereby forming an inclined top 6 for the stack. The various blocks in the several tiers are provided with interlocking tongues and grooves, as shown at 7, and similar tongues and grooves are formed between the blocks of the several tiers, as shown at 8, for the purpose of holding them securely in place, and said blocks are provided with internal transverse webs or braces 9 to strengthen the same. The blocks 5 of the upper tier are provided at their upper ends with the downwardly-projecting lips 10, which take over the upper end of the shell 2 of the stack, whereby said blocks are held in place, but the connection being such that the blocks can ride up and down on said shell as the masonry shaft 1 expands and contracts.

20 The top 11 of the furnace is substantially globe-shaped, as shown, and springs from the outer wall of the stack, so that an enlarged substantially globe-shaped chamber 12 is formed at the top of the stack. This top comprises the 25 globe-shaped metal shell 13, which is secured to the shell 2 of the stack a short distance below the upper edge of the latter and is provided with the refractory lining 14, which extends down into the space between the shell 2 and the shell 13, as shown at 15, a slight clearance-space 16 being left between the overhanging lips 10 of the blocks 5 and said lining, so that there is no friction between said parts in order that the stack 1 may expand and contract 30 freely without affecting the top. Extending through the walls of this globe-shaped top are the gas-ports 17, to which are connected the downcomers 18, said ports being provided at their tops with the explosion-doors 19, as is 35 common in blast-furnaces. The lower walls 20 of these gas-ports are substantially on a line with the inclined face 6 of the top of the stack, so that a straight and free passage of the gases out of the furnace-chamber to the 40 downcomers and explosion-doors is provided.

45 Extending through the top of the furnace is the hopper 21, which is composed of a series of segments 22, which, as shown in Figs. 2 and 3, comprise a quadrant of a circle; but 50 they may comprise any other segment either greater or less than a quadrant, if desired. These segments form the side walls of the hopper, and they are provided at their lower ends with the internal flanges 23, upon which 55 rests the funnel-shaped bottom 24, said bottom having an opening which is closed by the usual bell 25 and being held from rising under the pressure of the gases by the detachable rods 26. By this construction it is 60 possible to raise the bell and bottom of the hopper out of the furnace by merely removing the rods 26. The segments 22 are each cored out or cast about suitable pipes, which extend down into the same, as at 27 and 28, 65 and along the lower edge of said segment and through the flange 23 thereof, being connected at their outer ends, as at 29. To the up-

per ends of these pipes 27 and 28 suitable water connections are made, so that water will flow in, for instance, down through the pipe 27 and around through the flange 23 to the end 29 and back and up through the pipe 28 to the outlet. This construction effectively water-cools the lower edges of the segments 22 and prevents the same from burning out. These segments are also provided with the external vertical ribs 30 and the horizontal ribs 31, upon the latter of which rest the lower ends of brackets 32, which are bolted to the ribs 30 of said segments and connected to the furnace-top 13 and embedded in refractory material 33. This construction provides a strong and well-braced top for the furnace.

70 The hopper 21 projects down into the furnace-chamber, so that its outlet-opening, as at 34, is somewhat below the top of the stack, and this prevents the feeding of so much stock into the furnace that it will come close to the top of the furnace, whereby an extensive open space or chamber is always insured. The globe-shaped top 11, furthermore, springs outwardly from the exterior of the stack and at a point which is but slightly below the outlet from the hopper, so that the largest 75 diameter of the globe-shaped chamber in the top is above the outlet from the hopper, thereby increasing the space or chamber existing at the top of the furnace. Consequently when an explosion of gases occurs they will expand 80 into this chamber or space, thereby greatly reducing the liability of damaging the top of the furnace. Furthermore, the gas-ports 17 are so located in the top as to be in a straight line with the inclined top face 6 of the stack, 85 whereby a straight path is provided for such expanding gases to the explosion-doors 19, thereby further reducing the liability of damaging the top during explosion. These gas-ports 17 are located a considerable distance 90 above the outlet of the hopper, so that any fine ores which may be carried upward by the gases will have ample opportunity to again settle and return to the furnace-chamber before reaching the downcomers 18. The 95 straight faces 20 of the gas-ports and corresponding faces 6 on the top of the stack prevent the lodgment of these fine ores, and thus facilitate their return to the furnace-chamber. As a further aid to prevent the rise and 100 escape of the fine ores the top of the stack may be provided with an internal annular projection, as shown at 35, Fig. 5, which is preferably formed by suitably shaping the blocks 4 and 5 when the latter are used; but 105 in case no hollow blocks are used on the top of the furnace the masonry walls will be arched 110 in the manner shown.

115 What I claim as my invention, and desire to secure by Letters Patent, is—

120 1. A blast-furnace having a shaft, a globe-shaped top on said shaft providing a substantially globe-shaped chamber having an unobstructed annular passage to the furnace-

chamber, and a hopper projecting through said top and extending down into the globe-shaped chamber with its discharge end below the largest diameter of said globe-shaped chamber, whereby an enlarged space is provided to allow for the expansion of gases in an explosion.

2. A blast-furnace having a shaft, a globe-shaped top springing from said shaft providing a substantially globe-shaped chamber having an unobstructed annular passage to the furnace-chamber, a hopper projecting through said top and extending downward into the globe-shaped chamber with its discharge end below the largest diameter of said globe-shaped chamber, whereby an enlarged space is provided to allow for the expansion of gases in an explosion, a gas-port extending through said globe-shaped top, and a downcomer connected to said port.

3. A blast-furnace having a masonry shaft, a metal shell around said shaft, a globe-shaped top springing from said shell and providing a substantially globe-shaped chamber having an unobstructed annular passage to the furnace-chamber, and a hopper projecting through said top and extending down into the globe-shaped chamber with its discharge end below the largest diameter of said globe-shaped chamber, whereby an enlarged space is provided to allow for the expansion of gases in an explosion.

4. A blast-furnace having a masonry shaft, a metal shell around said shaft, a globe-shaped top springing from said shell and providing a substantially globe-shaped chamber having an unobstructed annular passage to the furnace-chamber, a hopper projecting through said top and extending downward into the globe-shaped chamber with its discharge end below the largest diameter of said globe-shaped chamber, a gas-port extending through said globe-shaped top, and an explosion-door at the outer end of said gas-port.

5. A blast-furnace having a masonry shaft, a metal shell around said shaft, a globe-shaped metal top springing from the outside of said metal shell below the top thereof, and a refractory lining for said globe-shaped top, the lower edge of said lining projecting down between the globe-shaped metal top and the metal shell for the stack and lying outside

the latter, whereby free expansion of the masonry shaft is permitted.

6. A blast-furnace having a masonry shaft, 55 a metal shell around said shaft, the top of said shaft being formed of blocks having lips which are hooked over said shell, a globe-shaped metal top springing from the outside of said metal shell below the top thereof, and a refractory lining for said globe-shaped top, the lower edge of said lining projecting down between the globe-shaped top and metal shell for the stack and lying out of contact with the overhanging lips of the blocks on the top 60 of the shaft.

7. A blast-furnace having a masonry shaft provided with an inclined upper face, a metal shell around said shaft, a globe-shaped top springing from said shell and providing a substantially globe-shaped chamber having an unobstructed annular passage to the furnace-chamber, a hopper projecting through the top and extending downward in the globe-shaped chamber with its discharge end below 70 the largest diameter of said globe-shaped chamber, a gas-port extending through said globe-shaped top and substantially in line with the inclined upper face of the masonry shaft, and an explosion-door at the outer end 75 of said gas-port.

8. A blast-furnace having a masonry shaft the top of which is formed by one or more tiers of hollow cast-metal blocks, said blocks being below the discharge end of the hopper 80 and the gas-ports.

9. A blast-furnace having a masonry shaft the top of which is formed by one or more tiers of interlocking hollow blocks.

10. A blast-furnace having a masonry shaft 90 the top of which is formed of closed hollow cast-metal blocks provided with inclined upper faces, said blocks being below the discharge end of the hopper and the gas-ports.

11. A blast-furnace having a masonry shaft, 95 and a metal shell around said shaft, the top of said shaft being formed of hollow blocks having lips which hook over said shell.

In testimony whereof I, the said PATRICK MEEHAN, have hereunto set my hand.

PATRICK MEEHAN.
